WILLIAM L. BARRON, OF NEW YORK, N. Y., AND FRITZ E. OSOL, OF ELIZABETH, NEW JERSEY, ASSIGNORS TO THE SINGER MANUFACTURING COMPANY, A CORPORATION OF NEW JERSEY.

SEWING-MACHINE GUIDE.

1,246,030.

Specification of Letters Patent.

Patented Nov. 6, 1917.

Application filed February 28, 1914. Serial No. 821,639.

To all whom it may concern:

Be it known that we, WILLIAM L. BARRON and FRITZ E. OSOL, citizens of the United States, residing, respectively, at New York, 5 in the county and State of New York, and Elizabeth, in the county of Union and State of New Jersey, have invented certain new and useful Improvements in Sewing-Machine Guides, of which the following is a 10 specification, reference being had therein to the accompanying drawings.

This invention has for its primary object to provide a simple and effective device for opening out the uniting seams of superposed 15 plies of fabric stitched together along their marginal portions for application of covering or fastening seams at their junctions.

In its preferred form, the improvement consists in a guide formed of a sheet-metal 20 plate having on opposite edges at one end lateral wings which are bent over the body of the plate toward each other but spaced apart to form a work-guiding channel having a longitudinal opening in its upper side, 25 said plate having secured thereto one end of a spring-plate whose opposite end extends within the channel and sustains a guide-tongue affording a partition for the channel directed intermediate the edges of said 30 opening. As thus constructed, the guide affords an upwardly contracted partitioned channel to receive the marginal portions of the two plies of fabric which are separated by the guide-tongue entering the crease between them and spread apart laterally by 35 the supporting spring-plate sufficiently to be flattened out by the action of the presser-foot, the throat-plate and the feeding device of the sewing machine at the stitching point.

40 The essential elements of the guide are the spaced and opposed edges of the wings which confine between them the parts of the superposed plies of fabric containing the initial uniting seam, and the upper or outer 45 edge of the guide-tongue which enters the crease between the plies at such seam; these relatively yielding guiding elements engaging the work in such manner as to insure its proper direction to the stitching mechanism 50 with little or no assistance on the part of the operator whereby the guide is rendered substantially self-acting. This self-acting characteristic of the device is due to the guiding ridge or edge extending in the direction of

feed and defined by the upper and downwardly inclined edge of said guide-tongue. 55

The class of stitching mechanism preferably employed comprises two reciprocating needles spaced apart sufficiently to penetrate the extreme edges of the marginal portions 60 of fabric or embrace the same, as may be desired, combined with looper mechanism for interlooping with the needle threads a looper- or covering-thread overlying the 65 said marginal portions of fabric.

In the drawings, Figure 1 is a perspective view of the forward portion of a sewing machine having applied thereto a seam-opening guide constructed in accordance with the present improvement. Fig. 2 is a 70 sectional elevation of a portion of the work-plate with the guide represented in elevation, and Fig. 3 is a plan of the guide detached from the machine. Fig. 4 is a front end view of the guide with a section of the 75 work applied thereto. Fig. 5 is a perspective view of the spring-plate and guide-tongue carried thereby. Fig. 6 is a perspective view of a section of the work taken mainly from the lower side, but turned at one 80 end to expose a portion of the face thereof.

Fig. 1 represents a portion of a Singer double-chain-stitch machine of the No. 62 class, comprising the work-plate 1 sustaining the throat-plate 2 having the usual feed-dog openings to receive the feed-dog 3 and needle-openings for the laterally spaced needles 4 mounted in the usual clamp-block 5 at the lower end of the needle-bar 6 and cooperating with a single thread-carrying 90 looper (not shown). Opposed to the throat-plate and feed-dog is the foot-plate 7 pivotally connected with the shank 8 which is secured to the presser-bar 9. 95

As represented in the drawings, the depending flange 1' of the work-plate has the seat 1'' to which is secured by means of the fastening screw 10 the foot 11 of the attachment plate 12 formed in its upper face with a channel in which is fitted the slide-plate 100 13. Upon the slide-plate 13 is secured by suitable means, one end of the base or channel-plate 14 having at its opposite end the lateral wings 15 which are bent over the body of the plate to bring their extreme 105 edges 15' into parallelism but slightly spaced apart so as to form with the body of the channel-plate a work-guiding channel hav-

ing a longitudinal opening disposed at the top and intermediate its side walls.

The base or channel-plate 14 has secured thereon in advance of the wings 15 by means 5 of the screw 16 one apertured end 17' of a spring-plate 17 with a slightly upturned and tapered opposite end portion 17" sustaining the centrally disposed longitudinal guide-rib or tongue 18 with a forwardly and 10 downwardly inclined operative edge 18' merging into the forward extremity of the spring-plate portion 17", which enters the work-guiding channel between the wings 15 and sustains the tongue in a plane intermediate the guide-edges 15' of said wings. 15

From the drawing it will thus be seen that the guide-rib or tongue 18 has an upwardly directed separating edge 18" indicated at the right of Figs. 2 and 5 which 20 merges into a downwardly inclined guide-ridge or edge 18' extending in the direction of feed toward the presser-foot. The upwardly directed edge 18" separates or parts the margins of the material as they advance 25 toward the needles. The guiding ridge or edge 18' is parallel to the edges 15' of the lateral wings 15, and these parallel edges control the passage of the material to the stitching point and insure travel of the 30 uniting seam in a direction midway between the needles. The length of the guide-ridge or edge is such that hand guiding assistance is not required from the operator to centralize the uniting seam between the needles. 35

As represented in Fig. 2, the attachment plate 12 is recessed to receive the detent-spring 19 which bears upon the under face of the slide-plate 13 to maintain the guide in position.

In the use of the attachment, the two plies of fabric *a* and *b* are opened out on opposite sides of the uniting seam and their marginal portions *a'* and *b'* are inserted between the guiding edges 15' of the wings 15 and within 45 in the work-guiding channel with the operative edge 18' of the guide-tongue 18 entered in the crease between them, as represented in Fig. 4. The resilience of the spring sustaining plate 17 serves to press the 50 guide-tongue 18 within the crease at the uniting seam with the opposite faces of the plies at such seam in contact with the guiding edges 15' of the wings 15, while the plate 17 serves as a yielding bottom for 55 the channel to deflect the marginal portions *a'* and *b'* of the fabrics outwardly, so that in passing beneath the presser-foot the seam is effectively flattened out before penetration by the needles. The downward inclination 60 of the guiding edge 18' of the tongue 18 obviously facilitates the descent of the work to the level of the throat-plate so as to pass easily beneath the upturned forward portion of the presser-foot.

It will be observed that the lateral wings

15 and guide-rib or tongue 18 constitute three convergently disposed blades of which the adjacent guiding edges are spaced apart to afford work-free guiding openings or slots communicating laterally with the exterior of the guide to embrace the marginal portions of the overlapping plies of the material adjacent the uniting seam, the intermediate plate or tongue serving as a divider for such marginal portions which are laterally flared to form grooves upon opposite sides of the seam having walls which are yieldingly maintained in engagement with the laterally spaced edges of the other blades under the resiliency of the supporting plate 17 by which the blade 18 is sustained.

The needle-thread loops may be connected together on the lower face of the work by means of the covering looper-thread *c*, or they may be locked in the work by separate threads to form independent seams in any usual or well known manner, and they may be so spaced apart as to penetrate the work either beyond or within the extreme edges 90 of the marginal portions *a'* and *b'* of the fabrics.

While the embodiment represented in the accompanying drawings, is the preferable one, it will be obvious that the present improvement is susceptible of considerable modification in the form and arrangement of its parts within the scope of the invention. It is to be understood, however, that a particularly important part of the improvement is the spring-pressed feature of the guide-tongue 18 which insures the proper engagement of such tongue with the work sustained in opposition thereto by the under faces of the wings 15. 100

Having thus set forth the nature of the invention, what we claim herein is:—

1. A sewing machine guide formed with a work-guiding channel having convergently inclined side walls with guiding edges separated by a longitudinally extending opening, and a guide-tongue yieldingly supported from within said channel in register with said opening. 110

2. A sewing machine guide formed with a work-guiding channel having a contracted longitudinally extending opening intermediate its side-walls and communicating laterally with the exterior of the guide, and having an edgewise yielding guide-tongue 120 disposed in a plane passing through said opening.

3. In a sewing machine having a multiple needle stitch-forming mechanism and presser-foot, a guide adapted to open out and spread the edges of two pieces of fabric adjacent a uniting seam therethrough, said guide being spaced from and in advance of the presser-foot and including a member having an upwardly directed separating 125

edge adapted to enter between the margins of the united fabric, said member also having a ridge merging into said edge and located in rear of the same adapted to be tracked by the uniting seam, said ridge being downwardly inclined toward the presser-foot, said separating edge and ridge of the member being in the same vertical plane parallel to the line of feed, a base-plate, and

10 wings overhanging said base-plate and terminating in edge portions spaced from and substantially parallel to said ridge whereby the work is led downwardly toward the presser-foot in a direction inclined to the

15 horizontal.

4. In a sewing machine having a multiple needle stitch-forming mechanism and presser-foot, a guide adapted to open out and spread the edges of two pieces of fabric

20 adjacent a uniting seam therethrough, said guide being spaced from and in advance of the presser-foot and including a member having an upwardly directed separating edge adapted to enter between the margins

25 of the fabric, a ridge merging into said edge and located in rear of the same adapted to be tracked by the uniting seam, said ridge being downwardly inclined toward the presser-foot, said separating edge and ridge

30 of the member being in the same vertical plane parallel to the line of feed, a base-plate, and wings overhanging said base-plate and terminating in edge portions spaced from and substantially parallel to

35 said ridge, said member having spreading elements coöoperating with the lower faces of said overhanging wings and diverging from said ridge for delivering the material with its margins in a flattened condition to the

40 presser-foot.

5. In a sewing machine having multiple needle stitching mechanism and a presser-

foot, and a guide adapted to open out and spread the edges of two pieces of fabric adjacent a seam therethrough, said guide being spaced from and in advance of the presser-foot and comprising a guiding ridge or edge extending in the direction of feed and two spaced longitudinally extending primary guiding elements coöperating therewith.

6. In a sewing machine provided with a multiple needle stitching mechanism, the combination of a presser-foot and a guide for opening out and spreading the edges of two pieces of fabric adjacent the seam therethrough, said guide being spaced from the presser-foot and comprising a base-plate provided at its forward end near the presser-foot with overhanging wings, and a yieldingly supported guide rib intermediate said wings.

7. In a sewing machine having multiple needle stitching mechanism, the combination of a presser-foot and a guide adapted to open out and spread the edges of two pieces of fabric adjacent a seam therethrough, said guide being spaced from the presser-foot and comprising a base-plate provided with bent-wing portions, a spring-plate superimposed on said base-plate and having a tapered forward end carrying a guiding rib within said bent-wing portions, said tapered forward end being adapted to further spread the edges of material after their spreading by the guiding rib.

In testimony whereof, we have signed our names to this specification, in the presence of two subscribing witnesses.

WILLIAM L. BARRON.
